E. RUSTERHOLZ,

FABRIC CUTTING MACHINE.

APPLICATION FILED JAN. 8, 1917.

1,246,327.

Patented Nov. 13, 1917.

X4 Inventor
Eugene Rusterholz
By his Attorney
Max Orduna

UNITED STATES PATENT OFFICE.

EUGENE RUSTERHOLZ, OF WEST HOBOKEN, NEW JERSEY.

FABRIC-CUTTING MACHINE.

1,246,327.

Specification of Letters Patent. Patented Nov. 13, 1917.

Application filed January 8, 1917. Serial No. 141,223.

To all whom it may concern:

Be it known that I, EUGENE RUSTERHOLZ, citizen of the United States of America, residing at West Hoboken, in the county of 5 Hudson and State of New Jersey, have invented certain new and useful Improvements in Fabric-Cutting Machines, of which the following is a specification.

In the embroidery art, scalloping machines are employed to cut around the scalloped edges of an embroidered piece of fabric, which machines consist of a fabric support, fabric feeding means and a frame carrying an endless flexible blade.

10 These machines, however, cannot be employed to cut between two rows of embroidered design so as to divide the fabric into strips or bands to be used as socalled insertions and as far as I am aware no machines 20 for this purpose have as yet been designed.

The main object of my invention is to provide a device whereby a piece of fabric containing a number of rows of embroidered designs can be easily and quickly cut up or divided into separate bands or strips.

Another object of my invention is to provide a device which can be easily and removably applied to the frame of the well-known scalloping machine without necessitating any change in the construction of the latter, except the removal of the movable blade.

A further object of my invention is to construct the device so as to render it adjustable 35 for different widths of bands or strips to be cut.

Another important object of my invention is to so arrange the cutting mechanism that when the point of the blade which cuts 40 the fabric becomes blunt, the blade can be displaced longitudinally to present a new sharp edge, so that the blade will be lasting and can be used for a considerable time before it need be replaced by a new blade.

45 With these and other objects in view my invention consists in the construction, arrangement and combination of parts, as will be hereinafter described and set forth in the appended claims.

50 In the drawing, which forms part of this specification, and in which similar reference characters denote corresponding parts, Figure 1 is a side elevation of my device shown as applied to the well known frame of a scalloping machine; Fig. 2 is an enlarged front view of the device; Fig. 3 is an

enlarged sectional side view thereof showing some details of construction and Fig. 4 is a cross section on line 4—4 of Fig. 3.

The hitherto used scalloping machine 60 comprises a table or support 1 which generally is composed of two sections which are separated on the central longitudinal line and on which the fabric 2 is supported. Suitably secured to the table or otherwise is 65 a frame 3 provided at its upper part with an arm 4 which extends longitudinally of the table and from the free end of which a tracer 15 is adjustably suspended. This tracer is adjusted to rest on the unembroidered part of the fabric and thereby prevents the embroidered part from coming into the path of the cutting mechanism.

The fabric is fed longitudinally of the table by a roller 5 coöperating with an endless band 6 guided over rollers or pulleys 7, 8.

75 Thus far the construction of the scalloping machine is well known and a further description and illustration of the details 80 thereof will not be necessary.

In lieu of the movable blade employed with these machines, I provide my new cutting device, which is constructed to be readily suspended from the arm 4 of the 85 frame of the scalloping machine.

90 My cutting mechanism substantially comprises a member or plate 10 which is provided with an oblong recess or opening 11 forming a socket and the upper and lower sides 11', 11'' of which are beveled (Figs. 2 and 3). Pivottally secured to the member 10 are arms 12, 12' which at their free ends are arched as at 12'' to correspond with the shape of the arm 4 so as to embrace the latter. The two arms are capable of being clamped together and around the arm 4 by means of a suitable clamping mechanism such as a bolt 13 and thumb nut 14. Engaging the socket 11 of the member 10, is the 100 blade carrier 9, which consists of a bar divided longitudinally and centrally into two sections 9' and 9'' between which the blade 16 is adapted to be clamped or otherwise secured. The sections are undercut at 9'' and 9'', so that when assembled they will form 105 between themselves a rest for the lower edge of the blade 16 and be capable of being tightened to securely hold the blade in position. The blade 16 is a flexible steel band 110 having a beveled or cutting edge 16' and adapted to extend longitudinally between

- the upper parts of the two sections of the bar 9 and to project with its sharp edge outwardly therefrom (Fig. 4). The section 9' of the carrier is formed at its rear end with 5 a projection 9⁶ conforming in shape with the cross section of the recess 11 and the end surface 9⁷ of said section is beveled so as to bear on the plate 10 when the projection 9⁶ engages the opening 11.
- 10 Owing to the shape of the opening 11 and of the projection 9⁶ the carrier 9 will extend at an angle to the member 10 which is suspended vertically, so that it will project slantingly into the path of the fabric, and 15 thus present to the latter a single point of the cutting edge 16'. When the cutting point becomes blunt, the knife can be displaced longitudinally to present a new cutting point, and so on.
- 20 The carrier is fixed in the socket 11 by a screw bolt 18 and washer 19 and can be adjusted in said socket toward one or the other end thereof. This enables the adjustment of the blade transversely to the path of the 25 fabric, according to the distances between two adjoining rows of embroideries.
- One of the chief advantages offered by my 30 invention is that the device can be used as an auxiliary implement for the well known scalloping machines, its attachment requiring no change of the machine except the removal of the movable cutting band.
- A further advantage is that the movable 35 blade used for the scalloping machine when accidentally severed can be utilized for my

device, by cutting the same into pieces to fit in the carrier.

While I have described and shown one embodiment of my invention, it is understood that various modifications may be made 40 in the construction without departing from the principle of my invention.

What I claim and desire to secure by Letters Patent is:

A cutting machine for embroidery fabric comprising a frame having an arm extending longitudinally of the fabric, a member having an oblong recess the upper and lower sides of which are beveled, a curved arm pivotally secured to said member and adapted to embrace and to be clamped to said arm, a blade carrier divided longitudinally into two sections, a flexible strip having a longitudinal cutting edge and serving as a blade, the sections of said carrier having each under cut portions to form when said sections are assembled a rest for the lower edge of said blade, the rear ends of said carrier being shaped to conform with the cross section of said oblong recess and to slidably engage the latter, and means for tightening said carrier in position within said recessed member.

In testimony whereof I affix my signature in presence of two witnesses.

EUGENE RUSTERHOLZ.
